UNITED STATES PATENT OFFICE.

CARL JOSEPH, OF BAYONNE, NEW JERSEY.

MANUFACTURE OF BOLT-ANCHORS.

1,111,749.

Specification of Letters Patent. Patented Sept. 29, 1914.

Application filed November 18, 1913. Serial No. 801,620.

To all whom it may concern:

Be it known that I, CARL JOSEPH, a subject of the Emperor of Germany, residing at Bayonne, in the county of Hudson and State of New Jersey, have invented certain new and useful Improvements in the Manufacture of Bolt-Anchors, of which the following is a specification.

This invention relates to the manufacture 10 of bolt anchors, and more particularly to that type disclosed in a patent issued to me on July 8, 1913, No. 1,066,500. The novelty consists in the construction of the blank, and the method of transforming it into a completed article.

In the drawings:—Figure 1 is a plan view 20 of the blank, out of which the anchor is formed. Fig. 2 is a side elevation of the blank partly formed into the anchor. Fig. 3 is a side elevation of the completed anchor. Figs. 4, 5 and 6 are, respectively, cross sectional views on the lines 4—4, 5—5 and 6—6 of Fig. 3. Fig. 7 is a longitudinal sectional view through the completed anchor. 25 Fig. 8 is a longitudinal sectional view, showing the screw hook secured by the said anchor.

Similar reference numerals designate corresponding parts in all the figures of the 30 drawings.

In the embodiment disclosed, a blank designated generally by the reference numeral 9, and shown in Fig. 1, is stamped or otherwise cut from sheet metal, to produce a central body portion 10 having an axial aperture 11 and a plurality of radially and angularly disposed segments 12, the said segments being joined to the body portion by reduced necks 13, and said segments tapering from their outer ends toward the center. 35 These segments have their edges serrated, as illustrated at 14, and their central portions are scored or indented along their radial axes, as illustrated at 15. The flat blank, as thus produced, is then bent to substantially the shape illustrated in Fig. 2. That is to say, the body 10 is first formed into substantially cup-shape, and the segments 12 are longitudinally creased inwardly, so that the said segments are substantially V-shaped in cross section, and the indentations or scores 15 are located at the apex of each, while the serrated edges are outwardly directed. The blank is then furthermore transformed into the shape illustrated in Fig. 3, which is the completed ar-

ticile. Briefly described, the body 10 is drawn into tubular or cylindrical form, and the segments 12 are disposed at one end of the same, with the serrated edges substantially in line with the walls of the body 10. As a result, the main portions of the segments incline inwardly, as will be clear by reference to Fig. 7, producing a contracted throat in line 65 with the bore of the body. When thus completed, the scores or indentations 15 constitute in effect a sectional screw thread.

In using the device, an opening, as 16, is first formed in the wall or object in which a bolt is to be anchored, and the anchor is introduced into this opening. If a screw bolt or other object, as 17, is then inserted into the anchor and is screwed thereinto, the threads 18 thereof will engage in the 75 scores or indentations 15, and the inserted object acting as a wedge, will force the segments apart, thus bringing the teeth or serrations 14 into biting engagement with the walls of the opening or socket 16. As a 80 result, the bolt or other article will be securely locked or anchored in the said opening or socket.

Having thus fully described my invention, what I claim as new, and desire to secure 85 by Letters Patent, is:—

1. A blank out of which to form a bolt anchor, comprising a central body and a series of symmetrically disposed radiating segments in angular relation to one another. 90
2. A blank out of which to form a bolt anchor, comprising a central body and a series of symmetrically disposed radiating segments disposed in angular relation to each other, each tapering from the outer end 95 toward the center.
3. A blank out of which to form a bolt anchor, comprising a central body and a series of symmetrically disposed radiating segments, each tapering from its outer end 100 toward the center along radial lines.
4. A blank out of which to form a bolt anchor, comprising a central body and a series of angularly and symmetrically disposed radiating segments, each tapering 105 from its end toward the center, each segment being serrated along its radial edges.

5. A blank out of which to form a bolt anchor comprising a central body and a series of angularly and symmetrically disposed radiating segments, each tapering from its end toward the center, each segment 110

- being scored or indented along its middle radial axis.
6. A blank for bolt anchors, comprising a central body, having an axial aperture, and radial segments projecting from the edge of the body and having reduced neck portions connected thereto in line with the aperture.
7. A blank for bolt anchors, comprising a central body having an axial aperture, and radial segments projecting from the edge of the body and having reduced neck portions connected thereto in line with the aperture, the edges of the segments being serrated, and said segments being scored or indented along their central radial axes, said serrations and indentations terminating short of the said neck portions.
8. The method of producing bolt anchors, which consists in forming a blank with a central body, and radially disposed segments and drawing the body to a tubular form with the segments at one end thereof.
9. The method of producing bolt anchors, which consists in forming a blank with a
- central body, and radially disposed segments, drawing the body to a tubular form with the segments at one end thereof, and insetting said segments into line with the bore of the body.
10. The method of producing bolt anchors, which consists in forming a metal blank with a central apertured body and radially disposed segments, longitudinally creasing said segments inwardly and taperingly, drawing the body to tubular form with the segments at one end thereof, and insetting said segments into line with the bore of the body to form a structure of substantially the same diameter throughout and with a contracted throat in line with the said bore of the body.

In testimony whereof I affix my signature in presence of two witnesses.

CARL JOSEPH.
